DESIGN FOR A DESK WRITING UNIT

Percival White, Long Ridge, N. Y.

Application June 30, 1944, Serial No. 114,274

Term of patent 3½ years

(Cl. D74—1)

To all whom it may concern:

Be it known that I, Percival White, a citizen of the United States and residing at Long Ridge, in the county of Westchester and State of New York, have invented a new, original, and ornamental Design for a Desk Writing Unit, of which the following is a specification, reference being had to the accompanying drawing, forming part thereof.

Fig. 1 is a perspective view of a desk writing unit showing my new design in a closed position; and Fig. 2 is a perspective view of the same in an open position.

I claim:

The ornamental design for a desk writing unit, substantially as shown.

PERCIVAL WHITE.
